UNITED STATES PATENT OFFICE.

AUGUST NORDEEN, OF CONNERSVILLE, INDIANA, ASSIGNOR, BY MESNE ASSIGNMENTS,
TO LAWRENCE MAXWELL, OF CINCINNATI, OHIO.

SECTIONAL ACCENTING DEVICE.

1,126,650.

Specification of Letters Patent. Patented Jan. 26, 1915.

Application filed April 30, 1912. Serial No. 694,158.

To all whom it may concern:

Be it known that I, AUGUST NORDEEN, a citizen of the United States, residing at Connersville, in the county of Fayette and State of Indiana, have invented a new and useful Sectional Accenting Device, of which the following is a specification.

This invention relates to that class of musical instruments in which the playing is controlled by a music sheet passing over a tracker or other equivalent device.

The principal objects of the invention are to provide simple and effective means for permitting the instrument to be played with a loud tone in any section or sections thereof, thus giving a solo effect, and especially to provide it in such form that it can be controlled automatically from the music sheet through extra tracker ducts or can be controlled at the will of the operator whether he is using a music sheet especially perforated for this purpose or otherwise. In other words, the operator can control the solo effect by hand alone or he can allow the paper to control it or if he desires, while it is under the control of the paper, he can vary the solo effect to suit his own ideas as to the playing of the music. In addition to this the invention involves exceedingly simple and practical means whereby the instrument can be left in normal condition with the sectional hammer rest rail retracted from the strings so that the entire instrument can be played with full loud tones and can be operated manually without restriction. Also the instrument can be left in such condition that the whole range of playing will be softened uniformly.

The invention involves other improvements in details of construction and combinations as will appear hereinafter.

Reference is to be had to the accompanying drawings in which—

Figure 1 is a front elevation of a portion of the action of a pneumatic musical instrument constructed in accordance with this invention. Fig. 2 is a fragmentary front elevation showing the indicator on the bottom of the tracker box and certain connections thereof; Fig. 3 is a plan of the indicating arrangement and other elements with the upper part removed and the side of the tracker box shown in section; Fig. 4 is a plan of the bottom plate of the parts shown in Fig. 3 with the elements above it re-

moved; Fig. 5 is a plan of the next plate above; Figs. 6 and 7 are plans of the next two plates above taken in order; Fig. 8 is a sectional view on the line 8—8 of Fig. 3; Fig. 9 is a sectional view on the line 9—9 which is drawn through Figs. 3, 4, 5, 6 and 7 to show where this section is taken on all of them; Fig. 10 is a plan of the top of the pneumatics for operating the rest rails and connected parts; Figs. 11 and 12 are plans of two of the plates below; Fig. 13 is a bottom plan of the bottom plate, and Fig. 14 is a sectional view on the line 14—14 of Figs. 10, 11, 12 and 13 showing the hammer rest rail operating device in elevation.

The invention is shown as applied to a type of instrument which is provided with the usual tracker box 10 and tracker 11 having the ordinary playing ducts 12 and additional ducts 13 the purpose of which will be hereinafter described. The connections 14 for rotating the music and take-up rolls need not be described in detail as any desired kind can be used.

The additional tracker ducts 13 are shown as of larger area than the ordinary ducts and of elongated form so that they remain in action longer. Each one is shown as connected, as for example by lead pipe 15, with a passage in a plate 17. This plate is located on the end of a plate 18 which has passages or perforations 19 communicating with these pipes. Below the plate 18 is a plate 20 having grooved passages 21 with which the passages 19 communicate. The other ends of the passages 21 communicate with passages or perforations 22 in a metal plate 23 and are adapted to be connected by a slide valve 24 with passages or perforations 25 in the same plate which communicate with grooved passages 26 in the plate 20. This slide valve is operated simply by a link 27 and button 28 movable over the surface of an indicator 29 which is provided with two symbols or words to indicate when the button is in position to render the device operative or inoperative. It will be obvious that this slide valve can be moved along in its guides 30 to connect the passages 22 and 25 or disconnect them.

When the passages 22 and 25 are connected an air impulse entering one of the tracker ducts 13 will pass along it into the passage 26, from that up to a passage or perforation 41 in the plate 18, up through

- passage 42 in an upper plate 43 spaced from the plate 18, and through lead pipe 44, or the like, arranged along the surface thereof into one of a series of boxes 45. These boxes 5 have chambers in the interior, each of which is connected with a chamber 46 in an upper plate 47. At the top of each chamber 46 is a simple primary pneumatic 48 which, under the influence of an air impulse, lifts a 10 valve 49 and connects a passage 50 in a plate 51, through a port 52, with a passage 53 in the same plate. Each passage 53 communicates through a passage 54 with an operating pneumatic 55. The passage 50 is constantly in communication through a pipe 56 with a source of exhaustion, not shown. Each passage 46 is shown as having a bleeding port 57 for a well known purpose. It 15 will be understood, of course, that there is one of these sources of connection for each of the auxiliary tracker ducts 13 and consequently there is a corresponding number of pneumatics 55. Each one of these pneumatics is provided with a spring 60 which normally would hold it expanded. The entrance of an impulse of air therefore into one of the auxiliary tracker ducts connects the corresponding pneumatic 55 with the source of exhaustion and collapses it in opposition to the spring. Each one of these 20 pneumatics is connected by its movable leaf 61 with an arm 62 which is integral with a rod 63 mounted to turn in a groove 64 on a support 65. Each rod is held in the groove 25 by a pair of cleats 66 and these parts constitute bearings for the rod in which each can turn. The arm 62 preferably is integral with one end of the rod and on its other end the rod has an integral arm 67 which 30 extends toward the stationary hammer rest rail 68. The arms 67 are arranged along the range of the instrument parallel with each other when in normal position and all extending toward this rail while the arms 62 35 extend forwardly of the instrument in order to be secured firmly to the movable leaves of their respective pneumatics. On each of the arms 67 is fixed an auxiliary hammer rest rail section 69 for moving the hammers 70 40 toward the strings 71 as will be understood. It will be obvious, that with the connections so far described, the normal positions of the pneumatics 55 is expanded in which position the hammer rest rail sections are 45 yieldingly pushed toward the strings so as to reduce the length of stroke of the hammers controlled by them. When an impulse of air enters one of the tracker ducts 13, it results in collapsing that particular pneumatic in opposition to its spring and thus 50 drawing that hammer rail section back into the dotted line position in Fig. 14, so that the hammers controlled thereby will have their full stroke and produce a loud effect. 55 By pressing the sectional rail toward the

strings yieldingly and retracting them pneumatically the springs are always ready to perform their office, and yet do not operate quickly enough to make any noise. At the same time their operation is limited by the expansibility of the pneumatic so the rail sections are left in uniform position.

It has been stated that the manual operation of the slide valve 24 will disconnect all of these tracker ducts 13 simultaneously from the connections which operate the pneumatics, so that the tracker ducts will be inoperative to affect the position of the hammers. Under these conditions the pneumatics will remain expanded and can be controlled manually by an indicating device, such as that shown in the patent to Peter Welin, No. 928,296, granted July 20, 1909. For this purpose a sliding valve 31 is shown having a pair of notches or openings 32 85 therein. This valve is designed to be reciprocated on a metal plate 32^a by a lever 33. Its position is indicated by a pointer 34 on the modulating-accent indicator 35, all substantially as shown in the above mentioned 90 patent. The plate 36 on which this valve 31 moves is provided with ducts 37 of the same number as the auxiliary ducts 13 in the tracker. These ducts extend through the plate 32^a and connect individually 95 through passages 38 in a plate 39 and ports 40 in the plate 18 with the passages 26. In the present case, the grooved passages or chambers 38 in the plate 39 are made of such form that when the lever 33 is about 100 in the middle of its range of travel and the pointer 35 indicates "loud center" on the indicator two, or even three, of the passages 38 which connect with the central pneumatics 55 will be open to the air by means 105 of the ports 32. This will allow air to enter these passages 26 and deflate these pneumatics, and thus these sections of the instrument can be caused to produce loud effects by the manually controlled lever 33 no matter whether the tracker is connected with each of the operating channels by means of the slide valve 24 or not. It will be seen that by moving the lever 33, either to the right or left that the other sections on either 110 side can be brought into operative condition in the same way. The channels 38 can be so arranged that only one at a time, or a desired number can be opened at once.

Another feature of this instrument is the 115 provision of means whereby the entire set of pneumatics 55 can be collapsed at once, thus rendering all of the auxiliary sectional hammer rest rails inoperative and permitting the instrument to be played manually or to 120 be accented as a whole. For this purpose a rod 75 is arranged along the rear of these pneumatics and is provided with two offset sections 76 in alignment, arranged in bearings 77 on the frame. This rod is provided 125

with an integral handle 78 by which it can be turned back and forth in its bearings. The handle is connected by a link 79 with an arm 80 on the end of a vertical shaft 81. 5 This shaft is provided with another arm 82 connected by a link 83 with an operating handle 84. These parts are so designed that when the operating handle is pulled to its extreme position it brings the arm on top 10 of the shaft to a dead center so that it puts the rod in position to draw back all the hammer rest rail sections positively in opposition to the several springs. It is obvious that this system of connections also is with- 15 in the control of the operator so that he can draw back the entire set of hammer rest rails either part way or fully as he may desire, and keep them in that position as long as he may think necessary for the proper 20 playing of the music.

It will be understood, of course, that while I have shown the instrument and the auxiliary hammer rest rail as divided into six independently movable sections, this 25 number may be increased or decreased within the scope of this invention according to the effects desired. I am aware that while I have illustrated a particular embodiment of the invention and shown it as applied to a 30 well-known type of musical instrument, yet it is capable of embodiment in many other forms and application to practically all types of automatic playing devices. Therefore I do not wish to be limited to the de- 35 tails of construction herein shown and described, or to the particular type of instrument illustrated, but

What I do claim is:

1. In a music playing device, the combi- 40 nation with the strings, hammers, hammer rest rail, and an auxiliary rest rail consisting of a plurality of independent sections, of means for positively holding said sections retracted from the strings to any de- 45 sired degree, resilient means for normally pressing said sections independently toward the strings, and pneumatic means for re- tracting said sections individually.

2. In a music playing device, the combina- 50 tion with the strings, hammers, hammer rest rail, and an auxiliary rest rail consisting of a plurality of independent sections, each movable beyond the front of the hammer rest rail, of means for positively holding each 55 of said independent sections retracted from the strings individually to any desired degree.

3. In a music playing device, the combi- 60 nation with the tracker, strings, hammers, and a rest rail in a plurality of independent sections, of a system of levers for positively holding said sections retracted from the strings, resilient means for normally pressing said sections independently toward the 65 strings, pneumatic means controlled from

the tracker for retracting said sections individually, and manually operated means for rendering said pneumatic means inoperative.

4. In a music playing device, the combi- 70 nation with the tracker having ducts, strings, hammers, and a rest rail in a plurality of independently movable sections, of mechanical means for holding said sections in one extreme position, resilient means for normally pressing said sections in the opposite direction, and means controlled by the admission of air into certain of said tracker ducts, and independent of the first named means for retracting the said sections to 75 said extreme position individually.

5. In a music playing device, the combi- 80 nation with the tracker having ordinary playing ducts, and a plurality of additional ducts, strings, hammers, hammer rest rail, and an auxiliary rest rail in a plurality of 85 independent sections equal in number to the number of said additional ducts, of means controlled by the admission of air into each of said additional tracker ducts for retracting one of the said sections from the strings.

6. In a music playing device, the combi- 90 nation with the strings, a tracker having ducts, and a movable hammer rest rail, of means controlled by the admission of air 95 into one of said ducts for retracting the hammer rest rail from the strings, yielding means for moving the hammer rest rail toward the strings, and independent mechanical means for positively holding the 100 hammer rest rail retracted thus rendering the duct controlling means inoperative.

7. In a music playing device, the combi- 105 nation with the tracker having ducts, strings, hammers, hammer rest rail, and an auxiliary rest rail in a plurality of independent sections, of means for holding all of said sections retracted from the strings, resilient means for normally pressing said sections toward the strings, means controlled by the admission of air into certain of said tracker ducts for retracting the said sections from the strings individually, a hand operated slide valve for connecting and disconnecting all of said ducts with the 115 pneumatic simultaneously, and a manually controlled lever having connections for opening to the air the connections between the ducts and the pneumatics, independently of said slide valve.

8. In a music playing device, the combi- 120 nation with the strings, a tracker having ducts, and a movable hammer rest rail, of means controlled by the admission of air into one of said ducts for retracting the hammer 125 rest rail from the strings, yielding means for moving the hammer rest rail toward the strings in opposition to the retracting means, means for positively holding the hammer rest rail retracted, thus rendering the duct 130

- controlling means inoperative, a modulating accent indicator, and hand operated means coöperating therewith for opening any desired ones of the duct controlling means to 5 the air independently of the open or closed condition of said ducts to retract the rest rail from the strings at will.
9. In a music playing device, the combination with the strings, a movable hammer rest rail, and a tracker having ducts, of means controlled by the admission of air into one of said ducts for retracting said rest rail from the strings, a spring for moving said rest rail toward the strings, a 10 pivoted rod adapted to contract said spring, a link connected with said rod and movable to a position to swing the rod forward in the instrument to contract the spring, a shaft having an arm thereon with which 15 said link is pivotally connected, and means for swinging said shaft into such position that the arm and link are substantially parallel, and the link extends from one side of the shaft to the other, whereby it is on a 20 dead center.
10. In a music playing device, the combination with the strings, and hammer rest rail, of an auxiliary hammer rest rail, a rod mounted to turn in bearings and connected 25 with the auxiliary rail and having an arm, a pneumatic having a movable leaf to which the arm is connected, a tracker bar having a duct opening, connections from the duct opening to said pneumatic for collapsing the pneumatic when the duct opening is open, and independent means for positively collapsing the pneumatic.
11. In a musical instrument, the combination with a set of strings and a hammer rest rail, of a support located adjacent thereto and having longitudinal grooves therealong, a series of rods pivoted in said grooves, each rod having two arms extending therefrom, one set of arms projecting toward the hammer rest rail, and the other set away from it, a plurality of independently movable sectional rest rails, one connected with each of the first named arms, a corresponding number of pneumatics each having a movable leaf connected with one of the second arms, and means for operating said pneumatics.
12. In a musical instrument, the combination with a set of strings and a hammer rest rail, of a support located adjacent thereto and having longitudinal grooves therealong, a series of rods pivoted in said grooves, each rod having two arms extending therefrom, a plurality of independently movable sectional rest rails, each connected with an arm on one of the rods and a corresponding number of pneumatics each having a movable leaf connected with the other arm of a rod, a plurality of springs which coöperate with said arms for normally forcing said sectional rest rails toward the strings, and 50 means for retracting said springs to hold the sectional rest rails away from the strings.
13. In a musical instrument, the combination with a hammer rest rail, of a support located adjacent thereto and having longitudinal grooves therealong, a series of rods pivoted in said grooves, each rod having two arms extending therefrom, one set of arms projecting toward the hammer rest rail, and the other set away from it, a plurality of independently movable sectional rest rails, one connected with each of the first named arms, a corresponding number of pneumatics each having a movable leaf connected with one of the second arms, and means for operating said pneumatics.
14. In a musical instrument, the combination with a set of strings and a hammer rest rail, of a support located adjacent thereto and having longitudinal grooves therealong, a series of rods pivoted in said grooves, each rod having two arms extending therefrom, a plurality of independently movable sectional rest rails, each connected with an arm on one of the rods and a corresponding number of pneumatics each having a movable leaf connected with the other arm of a rod, means for operating said pneumatics, a plurality of springs which connect with one of the second arms for normally forcing said arms toward the strings, and means for retracting said springs to hold the sectional rest rails away from the strings.

In testimony whereof I have hereunto set my hand, in the presence of two subscribing witnesses.
